UNITED STATES PATENT OFFICE.

CHARLES M. HOFFMAN, OF CHICAGO, ILLINOIS.

BENDING DEVICE.

1,119,961.

Specification of Letters Patent.

Patented Dec. 8, 1914.

Application filed October 30, 1913. Serial No. 798,268.

To all whom it may concern:

Be it known that I, CHARLES M. HOFFMAN, a citizen of the United States, residing at Chicago, in the county of Cook and

5 State of Illinois, have invented certain new and useful Improvements in Bending Devices, of which the following is a specification.

This invention relates to devices for making bends in metal rods, pipes, tubes, etc., and its object is to provide a novel and improved bending device characterized by a sweep-arm which carries a bending roller engageable with the work to bend the same

15 around a former.

The invention also has for its object to provide means whereby the former may be adjusted relative to a stationary work holder and thus locate the bend in the work

20 at the desired point.

In order that the invention may be better understood, reference is had to the accompanying drawing, in which a perspective view of the device is shown.

25 Referring specifically to the drawing, 5 denotes a bed or base-plate adapted to be fastened down on a work bench, table or other support. Near one of the corners of the bed-plate is mounted an upstanding lug

30 6 having a horizontal aperture 7 through which the pipe or other work to be bent is passed, and whereby it is held. In the bed-plate is a series of apertures 8 extending in a row diagonally across the bed-plate and

35 parallel to the longitudinal axis of the aperture 7. In a selected one of the apertures 8 is mounted an upstanding pin or bolt 9 on which is fulcrumed a horizontal sweep arm which is forked, the fork branches 10 be-

40 ing spaced vertically, and their outer ends having aligned apertures to receive the pin 9. On the pin 9, between the fork branches, is also mounted a former around which the work is bent, said former comprising a hori-

45 zontally positioned roller 11 having a grooved periphery. The fork branches also

carry a pin or bolt 12 on which is mounted a bending roller 13 having a grooved periphery. The fork branches have a series of apertures 14 for the pin 12, into a selected 50 one of which the latter is placed. The series of apertures 14 runs in the direction of the length of the sweep arm, and by providing the same, the bending roller 13 may be set different distances from the former, and dif- 55 ferent sized bending rollers may be employed. The arm sweep has a grip 15.

In operation, the pipe or other piece of work 16 to be bent is inserted into the aperture 7, and between that portion of the 60 fork branches 10 lying between the rollers 11 and 13, the sweep arm being first swung to extend at a right angle to the work. The sweep arm is now swung around to carry the roller 13 around the roller 11, whereby 65 the desired bend is made in the work, the latter being bent around the roller 11. The point at which the bend is made can be readily varied by changing the position of the pin 9 relative to the lug 6, these parts 70 thus serving as a gage.

I claim:

A bending device comprising a bed plate having a series of apertures, a lug mounted on the bed plate and having a transverse 75 work-holding aperture, the aforesaid series of apertures in the bed plate being parallel to the longitudinal axis of said work-holding aperture, a pin mounted in a selected one of said series of apertures in the bed 80 plate, a sweep arm fulcrumed on the pin, said sweep arm having a longitudinal series of apertures, a former mounted on said pin, a pin mounted in a selected one of the apertures in the sweep arm, and a bending roller 85 mounted on the last mentioned pin.

In testimony whereof I affix my signature in presence of two witnesses.

CHARLES M. HOFFMAN.
